POWER-OPERATED HAMMER

Original application filed June 29, 1927, Serial No. 202,447. Divided and this application filed October 14, 1929. Serial No. 399,681.

This invention relates to power-operated hammers, this application being a division of our pending application Serial No. 202,447, filed June 29th, 1927.

5 The object of my invention is to provide improved means for adjustably supporting a power-operated hammer whereby the hammer may be adjusted both vertically and horizontally in a quick and ready manner.

10 In the accompanying drawings:

Fig. 1 is an end elevation.

Fig. 2 is a longitudinal section.

Fig. 3 is a top plan view partly broken away.

15 Fig. 4 is a section on the line 4—4 of Fig. 3.

Our improvements have been shown in connection with a hammer of the pneumatic type, although they are equally applicable to other types of hammer. Referring to the drawings, a horizontally-arranged fluid pressure cylinder is indicated at 89, to the valve mechanism of which air is supplied through the pipe 89' leading from any suitable source of supply where it may be provided with a 25 controlling valve not shown. 90 represents the piston rod which is provided with an enlarged head 91. The cylinder is secured to a slide 92 by straps 93. The slide 92 is slidably mounted for horizontal movement upon a support 92', a screw 94 threaded in the slide and held against axial movement by a yoke 95 being employed to adjust the slide and cylinder horizontally relatively to the support. The yoke is loosely mounted upon a pair of 30 rods 96 projecting from the support and coil springs 97 are interposed between the yoke, the support and the heads of the rods to cushion the shock. The support 92' is slidably mounted for vertical adjustment upon a pair of hollow standards 98 and counter weights 99 located within the standards and connected to the supports by cables 100 which pass over sheaves 101 are employed to counterbalance the weight of the support and cylinder.

35 The vertical adjustment of the cylinder 89 is effected by a fluid pressure cylinder 102 whose piston rod 103 is connected to the support and which receives air under pressure through pipes 104 leading to a suitable point of control, where they are

equipped with controlling valves. An anvil 105, mounted upon a suitable support 106 cooperates with the pneumatic hammer; this support 106 being preferably connected with the support 107 for the standards 98 by the 55 plates 108 and the upper ends of the columns further connected by a cross member 109, so as to lend rigidity to the structure.

The pneumatic hammer shown is one which has been particularly designed for the 60 purpose of cleaning large-sized castings, the castings being suspended between the piston and the anvil. The arrangement described furnishes a ready means for positioning the cylinder of the hammer to adapt it to the 65 castings to be cleaned by adjusting it horizontally by means of the screw 94 and vertically by the cylinder 102.

Having thus described our invention, we 70 claim:

1. In a device of the character described, a hammer mechanism, a movable slide to which said mechanism is connected, a stationary support for said slide, a screw having a threaded engagement with said slide to adjust the same on said support, a yoke to confine said screw against axial movement, rods projecting from said support upon which said yoke is slidably mounted, and buffer springs 75 on said rod for said yoke.

2. In a device of the character described, a pair of spaced up-rights, a support slidably mounted on said up-rights, a power hammer horizontally arranged on said support, a fluid pressure cylinder beneath said support 80 having its piston connected therewith, and means for counterbalancing the weight of said support and hammer.

3. In a device of the character described, a pair of spaced hollow uprights, a support 85 slidably mounted thereon, a power hammer horizontally mounted on said support, a pair of counterbalanced weights, one in each upright, connections between said weights and support, and a fluid pressure cylinder disposed beneath said support having its piston rod connected to said support.

4. In a device of the character described, a pair of spaced hollow uprights, a cross member connecting the upper ends thereof, a 90

support slidably mounted on said uprights, a power hammer horizontally mounted on said support, means for adjusting said hammer horizontally, a weight in each hollow upright, sheaves on said cross member, cables connecting the support and weights and passing about said sheaves, and a fluid pressure cylinder vertically disposed beneath said support having its piston rod connected therewith.

5. In a device of the character described, a power hammer having a horizontally arranged cylinder, a slide to which said cylinder is connected, a support for said slide, a screw having a threaded engagement with said slide, a yoke to normally confine said screw against axial movement, a pair of stationary rods upon which said yoke is slidably mounted, and a pair of confined coiled springs on each of said rods, one spring on each side of said yoke.

15. In a device of the character described, a hammer mechanism, a slide to which said mechanism is connected, a support for said slide, a screw having a threaded engagement with said slide, a yieldable yoke to normally confine said screw against axial movement, and yieldable means to normally confine the yoke against axial movement and cushion 20 the shock of the hammer blows.

In testimony whereof, we have hereunto set our hands this 1st day of October, 1929.

WILLIAM C. SPECK.
EUGENE BARKER.
